UNITED STATES PATENT OFFICE

ABRAM H. SMYTHE, OF ALEXANDRIA, VIRGINIA, ASSIGNOR TO THE EMERSON PUMP AND VALVE COMPANY, OF ALEXANDRIA, VIRGINIA, A CORPORATION OF VIRGINIA.

STEAM VACUUM-PUMP.

1,184,663.

Specification of Letters Patent.

Patented May 23, 1916.

Application filed January 27, 1916. Serial No. 74,636.

To all whom it may concern:

Be it known that I, ABRAM H. SMYTHE, a citizen of the United States of America, and resident of Alexandria, in the county of 5 Alexandria and State of Virginia, have invented certain new and useful Improvements in Steam Vacuum-Pumps, of which the following is a specification.

This invention relates to steam vacuum 10 pumps and has for its object in part the provision of novel means for controlling supplies of steam to the cylinders or jackets forming the vacuum chambers of pumps of this character, the said invention also including novel valve operating mechanism 15 whereby the said valve may be actuated or operated for controlling ducts leading to the cylinders without employing a great amount of steam or other motor driving 20 media.

A further object of this invention is to produce a controlling mechanism of the character indicated which will operate without the use of lubricants which would contaminate water being circulated by the pump 25 and a still further object of the invention is to provide novel means for balancing the valve to minimize the friction and reduce the requirements for power to operate the 30 said valve.

A still further object of this invention is to provide novel means whereby a valve of this character and its operating mechanism may be incased so that they are fully 35 protected from the elements or from dust, or from other injurious contents of the fluid being pumped.

With the foregoing and other objects in view, the invention consists in the details 40 of construction and in the arrangement and combination of parts to be hereinafter more fully set forth and claimed.

In describing the invention in detail, reference will be had to the accompanying 45 drawings forming part of this specification wherein like characters denote corresponding parts in the several views, and in which—

Figure 1 illustrates a view in elevation, 50 fragments of the cylinders or cases with the valve casing and motor for driving the same applied thereto; Fig. 2 illustrates an enlarged sectional view on the line 2—2 of Fig. 1; Fig. 3 illustrates a sectional view 55 on the line 3—3 of Fig. 2; Fig. 4 illustrates

a sectional view on a line corresponding with the line 4—4 of Fig. 3; Fig. 5 illustrates a perspective view of a valve and an arm associated with it; Fig. 6 illustrates a sectional view of the said valve; and Fig. 7 illustrates 60 a view in elevation, partly in section, of a valve driving gear.

In these drawings 10 denotes the cylinders or casings forming the condensing chambers and for the purpose of uniformity of terms, 65 these elements will be hereinafter referred to as cylinders, by which term is understood that I mean any casing, jacket or shell constituting a closure forming a chamber for the purpose intended. It is furthermore understood that these cylinders are to be supplied at their bottoms with controlling valves of any general type suitable for the purpose, one embodiment of these controlling valves being illustrated in the patent 70 to R. B. Emerson, numbered 773,133, dated Oct. 25, 1904.

The means for admitting steam to the cylinders includes a casing 11 having branches 12 and 13 with ducts 14 and 15 respectively, 80 which ducts merge or communicate with a valve chamber 16 formed in the casing. A steam supply pipe 17 is threaded in the wall of the casing and communicates with the valve chamber and the said valve chamber 85 contains a cup-shaped valve 18 having ports 19 and 20 adapted to be moved alternately into alignment or registry with the ducts 14 and 15 respectively, so that steam is admitted to the cylinders alternately as is common 90 in this class of pumps. The bottom of the valve has ports 19^a which admit steam to the under surface of the valve for the purpose of balancing the said valve and minimizing friction, due to the existence of the 95 pressure of the steam.

In the present embodiment of the invention, a valve driving motor and gear are provided and as here shown, the said motor comprises a three-cylinder steam engine 21 100 which may be of the general construction of the engine shown in the patent to W. R. Emerson, numbered 828,100, dated August 7, 1906, and therefore, the details of construction of said engine will not be given 105 except to say that the link coupling 22 is connected to a crank 23. The crank which is driven by the engine is connected to the crank shaft 24 and the said crank shaft is suitably journaled in a part of the struc- 110

ture forming the crank case. The crank shaft near its upper end has gear teeth 25 thereon which engage the teeth of a gear wheel 26. The gear wheel 26 is rotatable 5 on a stud 27 and carries a pin 28 which, in the present embodiment of the invention, is threaded in an aperture 29 in said gear wheel 26. The upper extremity 30 of the crank shaft 24 enters a recess 31 formed in 10 the lower wall of the valve and the valve is rotatable or partially rotatable on the upper end of the said crank shaft. The valve is further provided with an arm 32 having a longitudinally disposed slot 33 into which 15 the pin 28 extends when the parts are in assembled relation and as the gear wheel 26 rotates, the pin 28 communicates motion to the arm 32 and oscillates the said arm, thereby communicating partial rotary motion 20 to the valve to effect the relation of the ports and ducts heretofore described and to alternately connect the steam supply pipe with the ducts for delivering steam to the cylinders.

25 The branches 12 and 13 have flanges 34 and 35 respectively, which are secured in known manner to flanges of the cylinders and the ducts preferably terminate in flared or enlarged openings where they communicate with the cylinders. In order to insure spreading of the jet of steam within the cylinders, a spider 36 is formed at the exit 30 openings of the ducts and it has been found in practice that when steam is so spread, the action of the condensing medium is more 35 uniform and sudden than when the steam is delivered in an unbroken or scattered jet.

The valve mechanism heretofore described being intended for use in connection with 40 a steam vacuum pump in which steam is admitted to the cylinders 10 and condensed therein by cooling the steam, as by the introduction of water into the cylinders, it follows that when the pistons of the motor 45 are operated they rotate, (through the connecting rod and parts associated therewith) the crank shaft having the gear teeth 25 and the gear teeth in turn mesh with the teeth of the gear wheel 26, thus the gear wheel is 50 rotated as stated heretofore in the specification. The gear wheel 26 is rotated on the stud 27 which carries the pin 28 which is threaded in the aperture 29 in the gear wheel 26, so that when the gear wheel 26 is rotated, 55 it carries the pin 28. The valve has an arm 32 with a slot in which the pin 28 moves so that as the gear wheel 26 is rotated and as the pin 28 rides in the slot of the arm, the

valve is oscillated. The valve has ports which register, in certain positions, with ducts leading to the cylinders and the relation is such that this valve controls the passage of steam which is delivered to the pipe 60 17 so that said steam reaches the cylinders alternately, it being understood that when 65 steam is being delivered to one cylinder, steam which had previously been delivered to the other cylinder is being condensed by water delivered thereto as well known in this art. The continuous movement, therefore, of the motor, for operating the valve, 70 controls the supply of steam to the cylinders.

I claim—

1. In a device relating to vacuum pumps, 75 cylinders, a valve casing having a valve chamber, branches extending from the valve casing, said branches having ducts communicating with the valve chamber, a cup-shaped valve oscillatably mounted in the 80 valve casing, said valve having ports for communicating alternately with the ducts, a slotted arm rigid with the said valve, said valve having a recess in its bottom, a crank 85 shaft having its extremity seated in the recess of the valve and forming a bearing for said valve, gear teeth on the crank shaft, a gear wheel mounted to rotate in the casing and meshing with the gear teeth of the 90 crank shaft, a pin on said wheel extending into the slot of the arm for communicating motion to the arm, and means for rotating the crank shaft.

2. In a device relating to vacuum pumps, 95 cylinders, a valve casing having branches secured to the cylinders, said branches having ducts communicating with the interior of the cylinders, a cup-shaped valve having ports in its side walls for alternately communicating with the ducts, the bottom wall 100 of said valve having ports therein for admitting steam to equalize pressure on the said valve, a slotted arm rigid with said valve, a gear wheel having a pin extending into the 105 slot of the arm, a crank shaft having teeth meshing with the gear wheel, the said valve having a seat in its under surface for the reception of the end of the crank shaft, and means for rotating the crank shaft.

In testimony whereof, I affix my signature 110 in the presence of two witnesses:

A. H. SMYTHE.
